CLAIM

We claim the ornamental design for a marine cleat, substantially as shown.

DESCRIPTION

FIG. 1 is a perspective view of the marine cleat of the present invention.

FIG. 2 is another perspective view of the cleat of the present invention.

FIG. 3 is a side elevation view of the cleat, with the opposite side having an identical appearance.

FIG. 4 is an end view of the cleat, with the opposite end having an identical appearance; and,

FIG. 5 is a top plan view of the cleat.

The broken lines in the drawings are for illustrative purposes only and form no part of the claimed design.
